United States Patent Office

Des. 227,943
Patented July 24, 1973

227,943

EYE SURGICAL TOOL

Ely Jay Crary, Marietta, Ga.
(4730 Austell Road, Austell, Ga. 30001)

Filed Apr. 5, 1971, Ser. No. 131,571

Term of patent 14 years

Int. Cl. D24—02

U.S. Cl. D83—12

FIG. 1 is a perspective view of an eye surgical tool embodying the new design;

FIG. 2 is a side elevational view thereof;

FIG. 3 is an enlarged left end elevational view thereof; and

FIG. 4 is an enlarged right end elevational view thereof.

I claim:

The ornamental design for an eye surgical tool, substantially as shown.
